[57] CLAIM

The ornamental design for a hair braiding tool, as shown and described.

DESCRIPTION

FIG. 1 is a front elevation showing my new design, a rear elevation is a mirror image thereof;

FIG. 2 is a top view thereof;

FIG. 3 is a bottom view thereof;

FIG. 4 is a right side view thereof; a left side view is a mirror image thereof; and,

FIG. 5; represents a plan view thereof in a reduced scale, showing my new design in use on a head of hair, the broken lines showing the hair being for illustrative purposes only and forming no part of the claimed design.

The undisclosed and partially obscured surfaces of the design are unornamented and follow the contours of the surfaces shown.
